BABY CARRIAGE RUNNING GEAR

Carl H. Kuniholm, Gardner, Mass., assignor to
 Kuniholm Manufacturing Company, Gardner,
 Mass., a corporation of Massachusetts

Application February 24, 1937, Serial No. 127,444

1 Claim. (Cl. 380—41)

This invention relates to baby carriages, go-carts and similar vehicles, and relates more particularly to the running gear with which such vehicles are provided.

5 It is the general object of my invention to provide an improved construction of running gear for such purposes, so devised that an effective yielding suspension is attained.

A further object is to provide a running gear 10 with yielding suspension, which gear is of simple and economical construction and which is particularly adapted to its intended purposes and conveniently applicable to different types of carriages.

15 My invention further relates to arrangements and combinations of parts which will be herein-after described and more particularly pointed out in the appended claim.

A preferred form of the invention is shown 20 in the drawings, in which

Fig. 1 is a side elevation of a baby carriage embodying my improvements;

Fig. 2 is an enlarged partial rear elevation, looking in the direction of the arrow 2 in Fig. 1;

25 Fig. 3 is an enlarged detail side elevation, looking in the direction of the arrow 3 in Fig. 2;

Fig. 4 is a view similar to Fig. 3 but showing the parts in a different relation;

Fig. 4a is a partial detail view to be described;

30 Fig. 5 is a detail view, looking in the direction of the arrow 5 in Fig. 3;

Fig. 6 is a side elevation of a holding clip, looking in the direction of the arrow 6 in Fig. 5; and

35 Fig. 7 is a detail end elevation, partly in section and showing a modified construction.

Referring to the drawings, I have shown a folding type of baby carriage or go-cart comprising a body 10 mounted on side bars 11, each 40 of which is directly secured at one end to the upper end of a folding side frame member 12 and is indirectly secured at the other end to the upper end of a second folding frame member 14.

The members 12 and 14 are pivoted at 15 to 45 a cross member 16, it being understood that a pair of side frame members 12 and 14 are provided at each side of the carriage.

The details of the body 10 and the manner of its attachment to the side frame members 12 50 and 14 form no part of my present invention and these parts may be of any usual or commercial construction.

The lower ends of the side frame members 12 are notched as indicated at 16 in Fig. 4a, and 55 are adapted to receive bearing portions 17 of

the rear wheel axle 18. The bearing portions 17 are held in the notches 16 by clips 20, riveted or otherwise secured to the lower ends of the member 12. These clips 20 each have an opening 21 to receive the axle and also have an outwardly projecting U-shaped portion 22 which at times acts as a stop, as will be hereinafter described.

The outer ends of the axle 18 are offset as indicated at 23 (Fig. 5) and are provided with 10 wheel bearing portions 24. The axle 18 is also provided with a middle portion 26 (Fig. 2) offset in the opposite direction from the wheel bearing portion 24, and connected by a stiff coil spring 28 to a cross bar 29 which is firmly secured at its ends to the side frame members 12. The wheels W may be secured on the wheel bearing portions 24 in any convenient manner, as by cotter-pins 30.

It will be understood that the front axle 32 20 (Fig. 1) is of identical construction and is secured in notches in the lower ends of the side frame members 14 by additional clips 20, all as previously described.

Having described the details of construction of 25 my improved running gear, the method of operation and advantages thereof are as follows:—

The springs 28 exert substantial tension on the middle offset portions 26 of the wheel axles 18 and 32, so that these parts normally assume 30 the position indicated in Fig. 3, with the oppositely offset portions 26 and 23 substantially aligned with the side frame members 12 or 14.

If a pair of wheels thus supported encounter an obstruction, the associated spring 28 allows 35 the axle to swing about its bearing portions 17 to the offset position shown in Fig. 4, thus allowing the wheels to rise without causing a corresponding lifting of the carriage body. If the obstruction is excessive, the body may eventually 40 be lifted but to a substantially reduced extent.

If the offset portions 23 are displaced to an exceptional extent, they will engage the outwardly projected portions 22 of the clips 20, by which angular movement of the wheel axle is 45 limited to not more than ninety degrees in either direction.

It will thus appear that I have provided an extremely simple and economical construction by which the wheels of a baby carriage or go- 50 cart or other similar vehicle may be yieldingly mounted and rendered adaptable to move to a substantial extent independent of the structure supported thereby, whenever obstacles are encountered. Obviously, the stiffness of the spring 55

suspension is in part dependent on the dimensions and tension of the springs 28, and any desired yield may be attained by suitable selection of the springs.

5 In Fig. 7 I have shown a slightly modified construction by which the wheels may be mounted to yield separately rather than in pairs. In Fig. 7 an offset brace 40 is secured to the lower end of a side frame member 41 and both the 10 side frame member and the brace are notched at their lower ends as previously described. A short axle 42 is mounted in the notches in the lower ends of the parts 40 and 41 and may be secured from displacement by a holding clip 43 15 as in the form previously described.

15 The axle 42 is provided with an offset bearing portion 45 at its outer end for the wheel W' and with an oppositely offset arm 46 at its inner end which is connected with a cross bar 47 by a 20 spring 48.

20 With this construction I attain the same yielding action with a single wheel W' as was attained for each pair of wheels in the construction shown in Figs. 1 to 5.

Having thus described my invention and the advantages thereof, I do not wish to be limited to the details herein disclosed, otherwise than as set forth in the claim, but what I claim is:

5 In a child's vehicle, a structure to be supported, a pair of wheels, an axle for said wheels, said axle having intermediate bearing portions pivotally mounted on said structure and wheel-bearing portions radially offset from said first-named bearing portions, clips to secure said axle 10 to said structure, and means to hold said wheel-bearing portions yieldingly in a predetermined normal angular relation to the adjacent fixed parts of said structure on which said axle is pivoted, said wheel-bearing portions being angularly and yieldably movable in both directions from said normal position on application of a displacing force thereto, and said clips having outwardly extending portions effective as stops to limit angular displacement of said wheel- 15 bearing portions in both instances.

CARL H. KUNIOLM.
